UNITED STATES PATENT OFFICE.

THOMAS MAITLAND CLELAND, OF SCARBORO-ON-THE-HUDSON, NEW YORK, ASSIGNOR TO INDIVIDUAL DRINKING CUP COMPANY, INC., OF EASTON, PENNSYLVANIA.

DESIGN FOR A CUP.

Application filed August 22, 1925. Serial No. 14,555. Term of patent 14 years.

To all whom it may concern:

Be it known that I, THOMAS MAITLAND CLELAND, a citizen of the United States, residing at Scarboro-on-the-Hudson, in the county of Westchester and State of New York, have invented a new, original, and ornamental Design for a Cup, of which the following is a specification, reference being had to the accompanying drawing forming part thereof.

The figure is a perspective view of the cup, showing my new design.

I claim:

The ornamental design for a cup, as shown.

T. M. CLELAND.
